H. A. FOOTHORAP.
TABULATING MECHANISM,
APPLICATION FILED AUG. 22, 1918.

1,349,824.

Patented Aug. 17, 1920.

Fig. 1.

UNITED STATES PATENT OFFICE.

HARRY ARTHUR FOOTHORAP, OF HARRISBURG, PENNSYLVANIA, ASSIGNOR TO ELLIOTT-FISHER COMPANY, OF HARRISBURG, PENNSYLVANIA, A CORPORATION OF DELAWARE.

TABULATING MECHANISM.

1,349,824.

Specification of Letters Patent. Patented Aug. 17, 1920.

Original application filed December 14, 1914, Serial No. 877,219. Divided and this application filed August 22, 1918. Serial No. 250,996.

To all whom it may concern:

Be it known that I, HARRY ARTHUR FOOTHORAP, citizen of the United States of America, residing at Harrisburg, in the 5 county of Dauphin and State of Pennsylvania, have invented certain new and useful Improvements in Tabulating Mechanism, of which the following is a specification.

10 This invention relates to typewriting machines and more particularly to a tabulating mechanism designed with special reference to the equipment of a typewriter of the flat platen type.

15 The object of the invention is to provide a tabulating mechanism of a simple and efficient construction adapted to be used either as a column tabulator or as a denominational or decimal tabulator and which may 20 be assembled in a compact unitary structure capable of bodily attachment to or detachment from the machine.

Other objects will appear as the succeeding description is developed.

25 In the accompanying drawings:

Figure 1 is a plan view of a portion of the typewriter equipped with my tabulating mechanism, certain of the parts being broken away to facilitate the disclosure.

30 Fig. 2 is a detail view showing the manner of retaining the tabulator stop bar.

Fig. 3 is a section on the line 3—3 of Fig. 2.

Fig. 4 is a sectional view of the tabulator 35 stop bar showing a tabulator stop in place thereon.

Fig. 5 is a detail view of one of the tabulator stops.

40 Typewriters of the character under consideration include a line space frame 1 which moves longitudinally over a flat platen, not shown, and supports a carriage 2 which is movable transversely of the platen on the frame. The specific character 45 of the frame and carriage, except as hereinafter mentioned, forms no part of the present invention and for that reason both are fragmentarily shown. Suffice it to say that the frame 1 is equipped with a pair of 50 brackets 3 which support the opposite ends of a tabulator stop bar 4, disposed parallel with the carriage in rear thereof. One end of the bar 4 is received in the seat 5 formed in a plate 6 secured to one of the brackets

3 and the other end of said bar is received 55 in an upwardly opening seat 7 in a similar plate 8 secured to the other bracket 3. One end of the bar 4 is placed in the seat 5 by an endwise movement of the bar whose opposite end is then dropped into the seat 7 60 where it is held against upward movement by a bar catch 9 pivotally mounted on the under side of the bar, as best shown in Fig. 2, and normally extended under a fixed part, as for instance, the plate 8. The 65 catch 9 may be swung from under the plate when it is desired to detach the bar from the frame and when swung back under the frame to secure the bar is arrested in its holding position by a stop lug 10 formed 70 on the catch and engaging the bar 4. To retain the bar 4 rigidly against endwise movement and also to afford slight endwise adjustment, thrust screws 11 are screwed through the brackets 3 and into 75 impinging relation with the ends of the bar 4 and are held by lock screws 12.

The front edge of the stop bar 4 is provided with a graduated series of teeth 13 designed to be engaged by the teeth 14 of 80 the tabulator stops 15, one of which is clearly shown in Figs. 1, 4, and 5. This stop 15 is preferably, though not necessarily, laminated, as shown in Fig. 5, and includes top and bottom plates 16 and 17, the former 85 being extended to the rear edge of the bar 4 and then bent to form a catch 16^a which engages under an inclined face 18 formed by removing the lower rear corner of the bar. This enables a stop to be readily placed 90 on the bar 4 in any desired position by inserting the teeth 14 in the teeth of the rack and then pressing down on the plate 16 until the catch thereof engages under the bar. The left hand faces of the teeth 13 of the 95 bar are straight since they sustain the thrust when the carriage is arrested and the teeth 14 of the stops are correspondingly formed. The blade engaging portion of the stop also has the form of a tooth with one side straight 100 and the other inclined so as to bring the stop within the limits of a letter space and to aid in the retraction of a tabulator blade without injury in the event of the retraction of the carriage with a blade slightly displaced from normal position.

The carriage 2, upon which the downwardly acting printing mechanism (not

shown) is mounted, includes in its organization a deck 19 which forms the bottom of the casing 20 within which the key levers and other elements of the key connections 5 are mounted. At the rear edge of this deck 19 and centrally located are a series of tabulator stops or blades 21 which are normally in non interfering relation with the tabulator stops 15 but are designed to be moved 10 rearwardly into such interfering or acting relation by the depression of suitable tabulator keys. Any number of these blades 21 may be provided but in the illustrated embodiment of the invention ten of these blades 15 are shown.

The structure herein claimed is also shown in Patent No. 1,280,697 dated October 8, 1918, issued on an application Serial #877-219 filed December 14, 1914, for Letters 20 Patent, of which this is a division.

It is thought that from the foregoing, the construction and operation of the described embodiment of my invention will be clearly understood, but I wish distinctly to reserve 25 the right to effect such changes, modifications or variations of the illustrated structure as may fall fairly within the scope of the protection prayed.

Having described my invention, what I 30 claim is:—

1. In a tabulating mechanism, the combination with a frame having seats, of a tabulator stop bar having its ends extended into

the seats and opposed to the frame to prevent material endwise movement of the bar, 35 one of said seats having an open side to permit the lateral withdrawal of the bar therefrom and a catch retaining the bar against lateral withdrawal from such open sided seat.

2. In a tabulating mechanism, the combination with a frame having oppositely disposed seats, one of which has an open side, of a tabulator bar having its ends extended 40 into the seats and a catch retaining one end of the bar against lateral withdrawal from the open sided seat, and thrust screws mounted in the frame and bearing against opposite ends of the bar to effect slight longitudinal adjustment of said bar and to 45 retain the same.

3. The combination with a toothed tabulator bar and tabulator blades, said bar having its lower rear corner beveled, of a tabulator stop having a plurality of teeth to 50 engage the toothed bar and having a single tooth to engage the tabulator blades and a top plate having an angular portion engaged over the bar and bent to form a catch engaging the beveled face of said bar.

In testimony whereof I affix my signature in the presence of two witnesses.

HARRY ARTHUR FOOTHORAP.
